UNITED STATES PATENT OFFICE.

ALEXANDER R. DUFF, OF TORONTO, ONTARIO, CANADA.

DRYING KILN.

Application filed June 7, 1922. Serial No. 566,477.

To all whom it may concern:

Be it known that I, ALEXANDER R. DUFF, of the city of Toronto, in the county of York, Province of Ontario, Canada, a subject of the King of Great Britain, have invented certain new and useful Improvements in Drying Kilns, of which the following is a specification.

This invention relates to kilns particularly adapted for drying and seasoning lumber, and my object is to devise a kiln which will dry every piece of lumber in a batch undergoing treatment uniformly and simultaneously, and in which perfect control of the rate of drying is obtained.

I attain my object by so constructing the kiln and arranging the lumber therein that a positively directed circulation of air, properly conditioned as to moisture content and temperature, is effected through the spaces formed in the lumber pile, means being provided for a controlled escape of moisture laden air and the introduction of outside air to take its place. The invention is hereinafter more fully described and is illustrated in the accompanying drawings in which—

Fig. 1 is a cross section of the kiln constructed in accordance with my invention; Fig. 2 is a longitudinal section of part of the same; and

Fig. 3 is a horizontal section on the line *a—a* in Fig. 2.

In the drawings like numerals of reference indicate corresponding parts in the different figures.

The kiln is constructed of any suitable material and in any desired manner to form the chamber 1, which will be provided at its ends with the usual doors. Within the chamber of the kiln are formed one or more air heating chimneys 2. These chimneys are of oblong form and extend substantially the whole length of the kiln. The bottom of each chimney is open and a plurality of openings 3 are formed in the top, one under each truck, these openings being preferably of less width than the width of the chimney. The top 4 also preferably slants upwardly from each side towards the opening or openings to facilitate the passage of air to these openings, and to bring the openings as close as possible to the bottom of the pile of lumber supported above the chimney as hereinafter described.

Within each chimney is located a suitable heating coil 5, this heating coil being located above the bottom of the chimney, and preferably close to the top. When the coils are suitably heated, air rises through the chimney and is heated in the process, constant circulation through the chimney being maintained as long as the coils are heated. These chimneys are so proportioned that though the circulation caused thereby is active the air does not move at a very high velocity. It is preferable that the chimneys extend sufficiently close to the bottom of the kiln to avoid dead air space, but not so low as to restrict the circulation of air under their bottom edges.

The effective utilization of the chimneys depend on a particular method of piling the lumber to be dried.

To support the lumber tracks 6 are provided extending longitudinally of the kiln, on which tracks run the wheeled trucks 7, the frames of these trucks being of open construction so as not to interfere with the free passage of air from the openings 3. The lumber 8 is piled longitudinally of these trucks, successive layers of lumber being separated by the narrow transverse separators 9. The lumber is stacked with a hollow center 10. The heated air passing from the opening or openings 3 rises up into the hollow center and follows the easiest path from the center to the outside of the pile, which is through the interstices of the pile laterally. This circulation is materially improved by making the hollow center taper inwardly and upwardly so that each successive layer of lumber projects slightly further into the hollow center than the layer underneath. This slight projection I have found has a very marked effect in deflecting rising air laterally through these interstices, particularly as the velocity of the circulating air is not great and its direction of movement is therefore easily changed. From the low velocity of the air it also results that the drying is very equable as the air will pass as readily out through the interstices of the lower part of the pile of lumber as it will higher up, which would not be the case if a forced circulation at higher velocity were maintained.

The preferred construction of the openings in the chimney tops is to form each chimney with one continuous opening, and

to use removable lids or plates 18, which are placed over such parts of the top of each chimney as are not immediately beneath a pile of lumber, thus ensuring the 5 passage of the air from the chimneys as far as possible taking place entirely into the heart of each lumber pile.

It is evident that a constant circulation of air will be maintained as long as the coils 10 are heated, and that this air will be brought into contact with the lumber at all parts of the pile, there being no center of the pile not reached by the circulating air, as is the case when lumber is piled in the ordinary manner and cured in kilns of the ordinary type.

It is essential to proper drying that moisture laden air be carried away and fresh outside air be introduced to supply its place. 20 It is also essential that means be provided to introduce at certain stages of the drying additional moisture into the air. It is therefore of importance that the fresh air and the introduced moisture be thoroughly mingled 25 with the circulating air before reaching the lumber. To attain these objects I provide the constructions I will now describe.

At each side of the kiln at intervals I provide the outlet air ducts 11, which preferably extend upwardly to the top of the kiln and communicates by means of damper controlled openings 12 with the interior of the kiln, preferably above the lower ends 30 of the chimneys 2. Under each chimney, and preferably below the level of the bottom 35 thereof, is provided a fresh air supply duct 13 provided at intervals with openings 14 in its top. Along the top of each duct run the steam pipes 15, in which are formed per- 40 forations so placed that the steam jets issuing from these pipes are directed into the chimney in such a way as to cross the paths of the circulating air and of the air issuing from the openings 14. The circulating air 45 and the fresh air are given every opportunity of picking up the moisture and the process is substantially completed, when the mingled circulating air, fresh air and steam passes through the heating coil 5. The air 50 is thus properly conditioned before it comes in contact with the lumber. The out flow of moist air, and therefore the entrance of fresh air is controlled by means of the dampers 12. As it is desirable that the circulation 55 in the kiln may be as symmetrical as possible, it is preferable to provide central air outlet ducts 16 corresponding in number to the air outlet ducts 11, which ducts are provided with lateral openings at their lower 60 ends controlled by dampers 17. At times the heat supplied by the steam from the steam spray pipes 14 may be sufficient to provide as rapid a circulation as may be necessary and at such times the steam supply to the 65 coils 5 may be cut off.

It is evident also that any other means of heating might be provided to take the place of the coils 5.

To ensure that none of the rising air from the chimneys will pass out from the hollow 70 centers of the lumber piles through the ends thereof, curtains may be hung on each end of each pile extending from the top of the pile to the top of the chimney, though this will not usually be necessary. 75

What I claim as my invention is:

1. In a kiln, the combination of a closed chamber; an air heating chimney adjacent the bottom of the kiln open at top and bottom; heating coils in said chimney above the 80 lower end thereof; means for admitting outside air to the lower part of the chimney; and an air outlet duct communicating with the interior of the kiln.

2. In a kiln, the combination of a closed 85 chamber; an air heating chimney adjacent the bottom of the kiln open at top and bottom; heating coils in said chimney above the lower end thereof; means for admitting outside air to the lower part of the chimney; 90 and an air outlet duct at each side of the chimney communicating with the interior of the kiln.

3. In a kiln, the combination of a closed 95 chamber; an air heating chimney adjacent the bottom of the kiln open at top and bottom; heating coils in said chimney above the lower end thereof; means for admitting outside air to the lower part of the chimney; an air outlet duct communicating with the 100 interior of the kiln; and means for injecting steam into the path of circulating air entering the lower end of the chimney and before it reaches the heating coils.

4. In a kiln, the combination of a closed 105 chamber; an air heating chimney adjacent the bottom of the kiln open at top and bottom; heating coils in said chimney above the lower end thereof; an inlet for outside air below the lower end of the chimney; and means for injecting steam into the path of 110 circulating air entering the lower end of the chimney and into the path of the outside air admitted between the air inlet and the heating coils.

5. In a kiln, the combination of a closed 115 chamber; an air heating chimney adjacent the bottom of the kiln open at top and bottom, the top opening being smaller than the bottom opening; heating coils in said chimney above the lower end thereof; means for admitting outside air to the lower part of the chimney; and an air outlet duct communicating with the interior of the kiln. 120

6. In a kiln, the combination of a closed 125 chamber; an air heating chimney adjacent the bottom of the kiln open at top and bottom; heating coils in said chimney above the lower end thereof; means for admitting outside air to the lower part of the chimney; 130

- lumber supporting means over the chimney open to permit of the upflow of air from the chimney; and a pile of lumber supported on said means formed with a hollow center over 5 the chimney substantially closed at the top, the pile also being formed with interstices extending laterally from the center to the outside of the pile.
7. In a kiln, the combination of a closed 10 chamber; an air heating chimney adjacent the bottom of the kiln open at top and bottom; heating coils in said chimney above the lower end thereof; means for admitting outside air to the lower part of the chimney; lumber supporting means over the chimney 15 open to permit of the upflow of air from the chimney; and a pile of lumber supported on said means formed with a hollow center over the chimney tapering at opposite sides 20 inwardly from the bottom towards the top, the pile also being formed with interstices extending laterally from the center to the outside of the pile.
8. In a kiln, the combination of a closed 25 chamber; an air heating chimney adjacent the bottom of the kiln open at top and bottom; means for admitting outside air to the lower part of the chimney; a steam pipe discharging steam into said chimney; and 30 an air outlet duct communicating with the interior of the kiln.
9. In a kiln, the combination of a closed chamber; an air heating chimney adjacent the bottom of the kiln open at top and bot- 35 tom; an inlet for outside air below the lower end of the chimney; and means for injecting steam into the path of circulating air entering the lower end of the chimney and into the path of the outside air admitted between the air inlet and the heating coils. 40
10. In a kiln, the combination of a closed chamber; an air heating chimney adjacent the bottom of the kiln continuously open at top and bottom; lids for closing parts of the top opening; heating coils in said chimney 45 above the lower end thereof; means for admitting outside air to the lower part of the chimney; and an air outlet duct communicating with the interior of the kiln.
11. In a kiln, the combination of a closed 50 chamber; an air heating chimney adjacent the bottom of the kiln open at top and bottom; heating coils in said chimney above the lower end thereof; means for admitting outside air to the lower part of the chimney; lumber supporting means over the chimney 55 open to permit of the upflow of air from the chimney; a pile of lumber supported on said means formed with a hollow center over the chimney tapering at opposite sides inwardly 60 from the bottom towards the top, the pile also being formed with interstices extending laterally from the center to the outside of the pile; and means for entirely closing the ends of the hollow center of the pile. 65

Signed at Toronto, Canada, this 23rd day of May, 1922.

ALEXANDER R. DUFF.
